(57) **CLAIM**

The ornamental design for a valve with flanges, as shown and described.

DESCRIPTION

FIG. 1 is a front, right perspective view from above of a valve with flanges showing the new design;

FIG. 2 is a front, right perspective view from below of the valve with flanges of FIG. 1;

FIG. 3 is a right side elevation view of the valve with flanges of FIG. 1;

FIG. 4 is a left side elevation view of the valve with flanges of FIG. 1;

FIG. 5 is a front elevation view of the valve with flanges of FIG. 1;

FIG. 6 is a rear elevation view of the valve with flanges in FIG. 1;

FIG. 7 is a top plan view of the valve with flanges of FIG. 1; and,

FIG. 8 is a bottom plan view of the valve with flanges of FIG. 1.

The broken lines shown in the figures are included for the purpose of illustrating portions of the valve with flanges and form no part of claimed design.
